TELEPHONE SYSTEM

Walter Pinell, Falkensee, Germany, assignor to
 Siemens & Halske Aktiengesellschaft, Werner-
 werk, Siemensstadt, near Berlin, Germany

Application December 4, 1936, Serial No. 114,102
 In Germany December 10, 1935

10 Claims. (Cl. 179—27)

The present invention relates to telephone systems, and more particularly to systems in which facilities are provided whereby, while a main connection is being held, subsidiary connections can 5 be set up over branch circuits associated with the main connection.

The invention may be applied with particular 10 advantage in telephone systems in which subscribers engaged in a call have the facility for establishing enquiry calls or for signalling a supervisory station and in which the setting up of the enquiry call or the transmission of signals is dependent upon whether an enquiry connection has been established or not between two like 15 switching measures which serve to initiate such connections. Previously in these systems a subscriber who after initiating an enquiry call by depressing a key, becomes convinced that the enquiry call is unnecessary or who has initiated an 20 enquiry call by depressing the key unintentionally, could only restore the connection to its original condition through the collaboration of the supervisory station, since by depressing the key again, the supervisory station is signalled.

25 According to the invention these complications in operation are avoided in that a subsidiary connection, which is initiated by effecting a manual operation a predetermined number of times, is released and the main connection is restored to its 30 original condition, if, prior to the completion of the subsidiary connection, the same manual operation is again effected a predetermined number of times.

In one embodiment an enquiry call is initiated 35 by performing a manual operation once and then dialling the required number, and a different subsidiary connection is initiated solely by performing the manual operation twice, a timing device becoming effective automatically, if impulses are not 40 transmitted within a predetermined time after an enquiry call has been initiated, whereby any subsequent performance of the manual operation is prevented from completing the other subsidiary connection but is effective in restoring the main 45 exchange connection to its original condition.

Since a few seconds always elapse between the time of effecting the first depression of the key to initiate an enquiry call and the time when the subscriber realizes that the setting up of an enquiry connection is not necessary, then if the enquiry connection is to be released again by a second depression of the key, the timing device will always have taken effect when the second depression of the key is performed.

50 According to the invention the arrangement

can alternatively be so arranged that the original condition of the connecting path is again set up by switching means under the influence of the enquiring subscriber only, in that the subscriber, if he wishes to neutralize the enquiry connection 5 without dialing numerical impulses, effects the same manual operation (depression of a key) twice in quick succession. The first depression of the key initiates the transmission of a signal to the operator, whilst the second depression of the 10 key controls devices which are set in readiness by the switching over operation for transmitting the signal, and bring about the re-establishment of the original condition of the connecting path. Thereupon the switching means serving to signal 15 the operator are also released.

In addition to systems adapted for the selective initiation of enquiry connections or for the transmission of signals, the invention is also applicable in remote communication systems. The 20 selective switching on of signals at various operating positions which can be connected to various points of a connecting path, or the selective operations of various signals at a single operating position may be referred to. If for example, the 25 operation of one signal is initiated by a single manual operation and the operation of another signal at a different point is effected by two manual operations, the invention makes it possible to suppress any inadvertent manual operation and 30 to re-establish the original condition of operation of the connecting path without requiring the co-operation of an operator.

For simplifying the operation to be executed 35 by the subscriber, the switching over devices and the auxiliary means for their control are so constructed that the subscriber need take no care as to the time during which he executes the switching operation in question so that he could thus effect switching measures, for example the 40 depression of a key, whether for initiating the different switching operations or for suppressing them without having to take into account how long these switching measures must last in order to effect the desired result.

The invention will be better understood from the following description taken in conjunction with the accompanying drawings, comprising Figs. 1, 2 and 3, which show three embodiments of the invention. All details, such as for example, controlling devices for seizing and setting connecting devices or for maintaining a connection, which are not necessary for the understanding of the invention, have been omitted for the sake of clarity since these are already known.

Figure 1 shows a portion of a public exchange line extending to a private branch exchange system, in which, dependent upon the varying number of times that the same switching operation is effected by a subscriber engaged in a call over this public exchange connecting line, either an enquiry call can be initiated or an operator can be signalled, and in which after an enquiry call has been initiated and the enquiry connection has not been set up, the switching over operations, which prepare the restoration of the original condition of the line by a further similar switching operation on the part of the subscriber, are effected by a time switch.

Fig. 2 which is a modification of the invention, shows a portion of a public exchange line extending to a private branch exchange system, in which after initiation of an enquiry call by a depression of the key, the original condition of the connection may be re-established if the enquiry connection has not been set up by a double operation of the same key. The relays A2, X2, Z2, Y2, V2, E2, Dr3 and Ar2 correspond in operation to relays having the same reference letters but 25 having the index 1 in Fig. 1.

Fig. 3, which is another modification of the invention, shows a portion of a public exchange line extending to a private branch exchange system, in which different signals are transmitted dependent upon the number of times the depression of the key is repeated by a subscriber.

Referring now to Fig. 1, when a call is initiated by a subscriber (not shown) in the private branch exchange, a battery feed loop circuit is completed 35 through the subscriber's telephone for both windings of relays A1 and X1 in series. In this circuit, only relay A1 is energized and not relay X1, since this is a differential relay. Relay A1 establishes a direct current bridge between the leads 1 and 40 7 of the public exchange line over its contact 4a1 in the following circuit; lead 1, contacts 2a1, 3a1, 4a1, relay Dr1, contacts 5a1, 6a1, and lead 7. The call in progress is maintained in the other exchange by the current flowing over this direct 45 current path. In addition, by opening its contact 8a1 relay A1 prevents the premature operation of relay E1. Relay Dr1 energizes over the above direct current path and at contact 26dr1 the circuit for relay V1 is prepared.

If the subscriber wishes to set up an enquiry call, while maintaining the public exchange connection, he operates a key at his station and thereby connects earth (positive) to lead 9. Winding II of the differential relay X1 is thereby 55 short-circuited and at the same time the current through winding I of this relay is increased. Relay X1 energizes and closes its contacts 10x1 and 11x1. For the present, however, only contact 10x1 is operative, because the contact 24y1, arranged in series with contact 11x1, is still open. Relay Z1 is energized the following way over its winding I; positive, contact 12y1, winding I of relay Z1, contacts 10x1, 13y1 and 14f1, and negative. Relay Z1 energizes and at contact 15z1 60 prepares a locking circuit over its winding II and the energizing winding I of relay Y1. Both windings are short-circuited by contacts 10x1 and 13y1. At contact 16z1 relay Z1 connects the choke coil Dr2 in shunt across leads 1 and 7 thereby ensuring the maintenance in the public 65 exchange of the connecting path throughout the duration of the enquiry call. At contacts 17z1 and 18z1 the enquiry line R1 is connected to the portion of the public exchange connecting path 70 leading to the subscriber and simultaneously the

portion of the public exchange connecting path leading to the public exchange is disconnected by the opening of contacts 3z1 and 5z1.

When a subscriber releases the key, relay X1 falls back and contacts 10x1 and 11x1 are open. 5 The following circuit is now completed: positive, contact 12y1, windings I and II of relay Z1, I of relay Y1, contacts 15z1, 14f1 and negative. Relay Y1 energizes. It closes contact 18y1 and then opens its contact 12y1 whereby the following locking circuit is established for relays Z1 and Y1: positive, contact 18y1, winding II of relay Y1, II of relay Z1, winding I of relay Y1, contacts 15z1, 14f1, and negative. Contact 19y1 is inserted in conductor 21 to prevent any premature 15 operation of the enquiry switching devices. On the release of the key by the subscriber and the subsequent energization of relay Y1 as described above, however, contact 19y1 is closed so that the following direct current bridge is established 20 between leads 20 and 21: lead 20, contacts 17z1, 4a1, relay Dr1, contacts 18z1, 19y1 and lead 21. By the current traversing this direct current bridge, a numerical impulse receiver serving to receive numerical impulses from the enquiring 25 station for setting up the enquiry connection, is set in readiness. At contact 22y1 a thermo-relay is connected up from: positive, contact 22y1, thermo-relay Th1, contact 23e1 and negative. The thermo-relay heats up. Contact 24y1 prepares for the transmission of signals to an operator.

When the subscriber transmits numerical impulses, these cause relay A1 to release and at contact 4a1 the impulses are transmitted to the 35 impulse receiver of the enquiry path. Moreover, the slow to release relay V1 is energized over contact 25a1 and thus by closing contact 27v1 establishes a circuit for itself independent of contact 26dr1, and at contact 28v1 short-circuits relay 40 Dr1 so as to ensure satisfactory impulse transmission. Relay Dr1 releases during the impulse train on account of the short-circuit. Relay V1 on the other hand remains energized, on account of its delayed release, during the opening of 45 contact 25a1 occurring during the impulse train.

The first numerical impulse for establishing the enquiry connection also causes relay E1, whose operation was prepared on the switching through of the enquiry line, to energize over the following 50 circuit: positive, contact 8a1, relay E1, contact 29y1 and negative. It locks up at contact 30e1 in a locking circuit independent of contact 8a1, shunt contact 13y1 by contact 31e1 and thereby prepares for the controlling of the switching over relay group A1 and Y1 by a further switching 55 measure on the part of the subscriber. The opening of contact 23e1 disconnects the thermo-relay Th1 before the latter has had time to operate and by the opening of contact 32e1 prevents the 60 operation of the relay F1, which causes the transmission of signals, due to any subsequent switching operation on the part of the subscriber.

When on the termination of the enquiry call, the enquiring subscriber wishes to re-establish 65 the original condition of the connecting path, he operates his key a second time, i. e., the same switching operation which was effective for initiating the enquiry call. On account of the connection to earth by the keys at the subscriber's 70 station relay X1 energizes again and closes contact 10x1. Since the contact 31e1, in series with contact 10x1, is closed, winding II of relay Z1 and winding I of relay Y1 are short-circuited. Relay Z1 releases and closes contacts 3z1 and 5z1 75

and opens contacts 15z1, 16z1, 17z1, and 18z1. In place of the choke-coil Dr2, relay Dr1 is again connected across the leads 1 to 7 so long as the subscriber holds the key down. Relay Y1 remains energized over: positive, contact 18y1, winding II of relay Y1, contacts 10x1, 31e1, 14f1 and negative. When the subscriber releases the key, relay XI falls back again and opens its contact 10x1, thereby breaking the locking circuit for relay Y1 which releases and restores all its contacts to normal.

The condition of the connecting path which was obtained before the first depression of the key by the subscriber (for initiating an enquiry call) is once more established.

If the subscriber wishes to signal an operator he has to depress the key at his station twice. By the first operation of the key the switching over relay group comprising relays Z1 and Y1 is operated in the same way as in the case of initiating an enquiry call. The second depression of the key influences relay F1, since the differential relay XI operating for the second time closes the following circuit: positive, contacts 24y1, 11x1, 25 relay F1, contacts 32e1, 33a1 and negative. Relay F1 energizes, establishes a locking circuit independent of contacts 11x1 and 24y1 by closing its contact 35f1 and opens contact 14f1 and thereby breaks the locking circuit over the windings 30 of relay Y1 and Z1 so that both these relays release and restore their contacts to normal with the result that the enquiry switching is released and the thermo-relay Th1 is disconnected before it energizes. At contact 36f1 the supervisory 35 lamp UL1 is switched on over: positive, contacts 37a1, 38f1, UL1 and negative.

If the operator after noting the lighting of the lamp UL1 wishes to connect to the public exchange line she operates the switch AT1 thereby 40 energizing relay AR1 which by opening contact 33a1 breaks the locking circuit for relay F1, disconnects the lamp UL1 at contact 37a1, at contact 38a1 connects the choke coil Dr2 across the leads 1 and 7 of the public exchange line and by 45 closing contacts 39a1 and 40a1 couples the branch line leading to the operator's speaking apparatus with the portion of the public exchange connecting path leading to the signalling subscriber, while simultaneously disconnecting 50 the leads 1 and 7.

If after the subscriber has conversed with the operator it is desired to re-establish the original condition of the connecting path, the operator restores the switch AT1 to normal and relay AR1 55 releases the switches through the speaking leads.

The case will now be considered in which the subscriber, after initiating an enquiry call, i. e., after the enquiry line RL has been connected up through the influencing of the switching over relay group Z1 and Y1, comes to the conclusion that the establishment of the enquiry call is unnecessary. The thermo-relay Th1 connected up at contact 22y1 becomes operative after a few seconds and closes its contact 41th1 and thereby 60 energizes relay E1 whose energizing circuit has been prepared at contact 29y1 when the first depression of the key which initiated the enquiry call, becomes operative. Relay E establishes a locking circuit independent of contact 41th1 at 65 contact 30e1, at contact 23e1 breaks the circuit for the thermo relay and by closing contact 31e1 prepares for the controlling of the switching over relay group Z1 and Y1 by a further similar switching operation (depression of the key) on 70 the part of the subscriber. When the subscriber 75

executes this switching operation relay XI energizes again and at contacts 10x1 short-circuits winding I of relay Y1 and winding II of relay Z1. Relay Z1 releases. After the key is released relay Y1 falls back as already described above.

The condition of the enquiry path obtained before the first depression of the key, which promoted the enquiry call is once more re-established. It should be mentioned that the second depression of the key does not result in connecting up the supervisory lamp UL1 in spite of the closing of contact 11x1 since relay E1 energized by the thermo-relay Th1 breaks the energizing circuit of relay F1 at contact 32e1.

Figure 2 shows the embodiment in which after 15 initiating an enquiry call by a depression of the key the original condition of the main connecting path may be re-established if the enquiry connecting path is not set up by a double operation of the same switching means (depression of the 20 key). The relays A2, X2, Z2, Y2, E2, Dr3 and Ar2 correspond in operation to the relays having the same reference letter but having the index 1 in Fig. 1.

During a call relay A2 is energized and its contact 58a2 is closed whereby relay Dr3 is connected across the leads 51 and 52 of the public exchange line, premature operation of relay E2 is prevented at contact 53a2, and contact 54a2 fulfills the same function for relay V2. If the 30 subscriber wishes to set up an enquiry call he earths his speaking line. Relay X2 energizes and closes contact 55a2. Relay Z2 is energized, closes its contacts 55z2, 56z2, 57z2 and 58z2 and opens its contacts 59z2 and 60z2. On releasing the key, 35 on account of the removal of the short-circuit about winding II of relay Z2 and winding I of relay Y2, relay Y2 energizes and opens its contact 61y2 and at contact 62y2 switches the enquiry line through. At contact 63y2 it prepares for the 40 energizing of relay E2 and at contact 64y2 it prepares for the controlling of the second switching over relay group comprising relays F2 and G2.

When the subscriber transmits numerical impulses for establishing the enquiry path, the relays E2 and V2 energize in the same way as do the relays E1 and V1 in the embodiment of Fig. 1. Relay E2 locks up at contact 65e2 in circuit independent of contact 53a2 and at contact 66e2 prepares for the controlling of the switching over 45 relay group Z2 and Y2 by a further depression of the key on the part of the subscriber and by opening contact 67e2 prevents the second switching over relay group comprising relays F2 and G2 from being controlled by the same depression of 50 the key by the subscriber. Relay V2 is energized during each impulse train since it establishes a locking circuit independent of contact 69dr3 at contact 68z2 and short-circuits relay Dr3 in the bridge across the enquiry line RL at contact 55 60 70v2.

If after terminating the enquiry call the subscriber desires to re-establish the original condition of the connecting path he operated his key once more. Relay X2 energizes and the winding 65 II of relay Z2 and the winding I of relay Y1 are short-circuited. Relay Z1 falls back, switches the speaking leads through to the public exchange line conductors 51 and 52 and disconnects the choke coil Dr4. On releasing the key 70 the circuit for winding II of relay Y2, completed over contact 70y2 is broken through the release of relay X2 and the opening of contact 55x2. Relay Y falls back and restores all its contact to the normal position shown in the drawings.

The condition obtained in the connecting path before the initiation of the enquiry call is now re-established.

- If the subscriber wishes to signal the operator by connecting up the lamp UL2 he has to depress his key twice. The first depression of the key results in the energizing of relays Z2 and Y2. At contact 64y2 preparation is made for controlling the relay group F2 and G2 and simultaneously, 10 by opening contact 61y2, the switching over relay group Z2 and Y2 is prevented from being influenced by the next depression of the key. When relay X2 energizes in response to the second depression of the key the following circuit 15 is established at contact 71x2: positive, contacts 64y2, 72f2, winding I of relay G2, contacts 71x2, 67e2, 73ar2 and negative. Relay G2 energizes and at contact 74g2 prepares a circuit over its winding II and the winding I of relay F2. On releasing the key, relay X2 falls back and opens contact 71x2. Relay F2 can now energize over the following circuit: positive, contacts 64y2, 72f2, windings I and II of relay G2, winding I of relay F2, contacts 74g2, 67e2, 73ar2 and negative. Relay F2 20 energizes and locks up by closing its contacts 78f2 and 76f2 in a circuit independent of contact 64y2: positive, contacts 78f2, 76f2, winding II of relay F2, winding II of relay G2, winding I of relay F2, contacts 74g2, 67e2, 73ar2 and negative. By the opening of contact 77f2 the locking circuit for relays Z2 and Y2 is broken. Both 25 relays accordingly release and restore their contacts to normal. Thus the enquiry connection is thereby released. At contact 79f2 a delay device for example a thermo-relay Th2 is connected up which becomes operative after a short time and connects up relay F3 at contact 80th2; positive, contacts 79f2, 80th2, relay F2 and negative. Relay F3 energizes, establishes a locking circuit 30 independent of contact 80th2 at contact 81f3, breaks the heating circuit for the relay Th2 at contact 82f3 and at contact 83f3 completes the circuit for the lamp UL2 from: positive, contacts, 84ar2, 83f3, lamp UL2 and negative. The operator connects up to the line leading to the subscriber transmitting the signal while at the same time disconnecting the leads 51 and 52 leading to the public exchange by operating the switch AT2 and thereby energizing relay A2 which 35 closes contacts 85ar2, 86ar2, and 81ar2, and opens contacts 88ar2 and 89ar2 the locking circuit for relays F2 and G2 is simultaneously open at contact 73ar2. The subscriber and the operator can now converse together. When the operator disconnects by restoring the switch AT2, relay Ar2 40 de-energizes and restores all the contacts to normal. The condition of the connecting path obtained before the first depression of the key is once more re-established.
- 60 The case will now be considered where the subscriber after executing the first switching operation (depression of the key) and thereby controlling the switching over relay group Z2 and Y2 to connect up the enquiry line RL, makes up his mind that the establishment of the enquiry call is unnecessary. In order to re-establish the original condition of the connecting path he operates the key at his station twice. By the first depression of the key, after that 65 initiating the enquiry call, the switching over relay group comprising relays G2 and F2 are controlled in the manner described, the thermo-relay Th2 heats up and delays the lighting of the supervisory lamp UL2. When now shortly 70 afterwards the subscriber depresses the key again 75

this has the consequence of energizing relay X2 which short-circuits winding II of relay G2 and winding I of relay F2. Relay G2 releases and opens its contact 74g2. Only relay F2 now remains connected up over its winding II from: positive, contacts 78f2, 76f2, winding II of relay F2, contacts 71x2, 67e2, 73ar2 and negative. On releasing the key, relay X2 falls back and opens the contact 71x2. Relay F2 releases and disconnects the thermo-relay. 10

The condition obtained before the inadvertent initiation of the enquiry call is once more re-established.

If the operator does not reply after the lamp UL2 has been lighted or if the subscriber decides 15 to abandon the connection to the operator before the latter has responded he has it in his power to re-establish the original condition of the connecting path. The switching over relay group G2 and F2 also serves this purpose. The 20 subscriber has merely to depress his key once more. Relay X2 energizes. At contact 71x2 winding II of relay G2 and winding I of relay F2 are short-circuited. Relay G2 releases. Contact 74g2 opens. On releasing the key, relay 25 X2 falls back and contact 71x2 opens. Relay F2 de-energizes and at contact 79f2 breaks the circuit for relay F3 or, if this has not yet been connected up, that of the thermo-relay Th2. Since contact 77f2 is also closed, the original 30 condition of the connecting path is re-established.

Figure 3 represents the invention applied to a system in which different signals are transmitted dependent upon the number of times a 35 switching operation (depression of a key) is repeated on the part of a subscriber. It is assumed that a lamp UL3, of the exchange VSt1 to which the subscriber is connected, is lighted by a single depression of the key, whilst when the switching 40 operation is operated twice, a lamp UL4 is lighted in the exchange VSt2. As before, battery feed is supplied to the calling subscriber by relays A3 and X3. Relay A3 over its contact 100a3 maintains energized relay A4 located in the bridge 45 arranged at the exchange VSt2 from: negative, winding I of relays X4 and A4, lead 101, contacts 124v4, 100a3, choke-coil Dr5, lead 104, windings II of relays A4 and X4, and positive. Relay X4 is a differential relay and cannot energize 50 in this circuit.

To light the lamp UL3, the subscriber operates his key and thereby applies earth to his speaking line conductors. Relay X3 operates and at contact 105x3 completes a circuit: positive, contact 106y3, winding I of relay Z3, contacts 105x3, 107y3, relay V3, contacts 108ar3, 136th3 and negative. Relays Z3 and Y3 energize. Relay V3 serves a purpose to be explained later. Relay Z3 at contact 109z3 prepares an energizing circuit over winding I of relay Y3 and a locking circuit over its own winding II. The relay V3 shunting this winding has so low a resistance that relay Y3 cannot energize so long as contact 105x3 is closed. When the key is released, relay 60 X3 de-energizes and contact 105x3 opens. Relay Y3 can now energize over its winding I. It connects up its own winding II in place of winding I of relay Z3 over contact 110y3 and at contact 111y3 prepares for connecting up the lamp 65 UL3. The contacts 112y3 and 113y3 which are likewise closed serve purposes to be explained later. The opening of contact 107y3 prevents any premature influencing of the switching over relay group Z3 and Y3. When, on account of 70 75

- the opening of contact 105x3, the slow to release relay V3 de-energizes, the circuit for the lamp UL3 is closed: positive, contacts 114v3, 111y3, 115v4, 116v5, 117ar3, lamp UL3 and negative.
- 5 The operator is informed by the lighting of the lamp UL3 that the subscriber wishes to converse with her. She operates the switch AT3 and thereby energizes relay Ar3 which connects a branch line leading to her speaking equipment
- 10 to the connecting path by closing contacts 118ar3 and 119ar3. Relay Ar3 by opening contacts 120ar3 and 121ar3 disconnects the connecting line leading to public exchanges, at contact 117ar3 breaks the circuit for the lamp UL3, and
- 15 at contact 108ar3 breaks the locking circuit for relays Z3 and Y3.

On the termination of the conversation between the subscriber and the operator the switch AT3 is restored, relay Ar3 releases and restores 20 its contacts to normal and the original condition is re-established.

The case will now be considered in which the subscriber wishes to signal the operator's station at the exchange VSt2. For this purpose he has 25 to depress the key at his station twice in quick succession. The first depression of the key once more controls the switching over relay group Z3 and Y3. Relay V3, which was energized, delays the lighting of lamp UL3 so that when the subscriber depresses the key a second time directly after the first, in order to operate the lamp at the operator's position at the exchange VSt2, the lighting of lamp UL3 is prevented in that the relay X3 energizing again in response to the 30 second depression of the key and closes, at contact 122x3, the circuit which was prepared for relay V4 at contact 112y3. This relay opens contact 115v4 thereby breaking the circuit for lamp UL3 and in addition prepares a circuit for relay 35 V5 at contact 123v4.

Relay V4, which is energized during the time that the key is depressed at the station and while relay X3 is energized also initiates the switching on of the signal at the operator's position in the 40 exchange VSt2. For this purpose it closes contact 124v4 and thereupon opens contact, 102v4. Winding II of relay X4 in the exchange VSt2 is disconnected and relay X4 is energized over its winding I, whilst relay A4 remains energized over 45 its winding I arranged in series with winding I of relay X4. Relay X4 closes contact 125x4 and thereby completes the following circuit: positive, contact 126y4, winding I of relay Z4, contact 125x4, relay V6, contact 131t, and negative. Relay Z4, at contact 127z4, prepares a circuit over 50 its winding II and over winding I of relay Y4, whilst relay V6 opens its contact 128v6 and thereby delays somewhat the switching on of lamp UL4 after the key is released. When the key is released by the subscriber, relay X3 falls back as does relay V4 which closes contact 102v4 and opens contact 124v4. Relay X4 de-energizes and 55 opens contact 125x4. Relay Y4 can now energize over its winding I, since the winding of relay V6 arranged in series over contact 125x4 is of so low a resistance that Y4 did not receive sufficient current to energize so long as contact 125x4 was closed. Contact 129y4 is closed. Winding II of relay Y4 is now connected up in place of winding I of relay Z4. Contact 130y is more 60 over closed and accordingly the lamp UL4 is lighted after relay V6 has released over the following circuit: positive, contacts 130y4, 128v6, 131t, lamp UL4 and negative.

75 In the exchange VSt1, the release of relay X3

completes the circuit for relay V5 which was prepared at contact 123v4 when relay V4 energized: positive, contacts 131x3, 123v4, 132v5, relay V5 and negative. Relay V5 closes its contact 133v5 and then opens its contact 132v5. It 5 has now established a locking circuit which is dependent only upon contact 113y3. The closing of contact 134v5 prepares a circuit for controlling of the switching over relay group Z3 and Y3 by the subscriber, whilst a thermo-relay Th3 is connected up at contact 135v5. The thermo-relay Th3 operates after a certain time and opens contact 136th3 and thereby causes the disconnection of relay Z3 and Y3. Relay V5 now also falls back since contact 113y3 is open. 10 15

When the operator at the exchange VSt2 enters the connection in response to the lighting of lamp UL4, the contacts 131t and 137t are opened in any desired manner and the lamp UL4 is disconnected while the locking circuit for relays Z4 and Y4 is broken. When at the termination of the conversation between the subscriber and operator at the exchange VSt2 the latter disconnects and contacts 131t and 137t are again closed the condition obtained before the subscriber effected the first switching operation is again established. 20 25

The case will now be considered in which the subscriber has inadvertently operated the key once. This results in the energizing of relays 30 Z3 and Y3 and also of relay V3 which delays the connecting up of the supervisory lamp UL3. If the subscriber now operated the key twice in quick succession, no lighting of the lamp UL4 occurs, but the original condition of the connecting path is re-established. If the key is depressed a second time by the subscriber after relay V3 has already released, the transitory switching on of the lamp UL3 has no significance since some time must always elapse before the 35 operator enters the connection after the lamp has lit up. The slow operating relay V3 can however be made sufficiently slow to operate so that in the majority of cases operation of the lamp UL3 is definitely prevented. 40 45

The second depression of the key on the part of the subscriber causes relays V4, X4 and Z4 to energize again and after the key has been released relays V5 and Y4 energize. If now the subscriber depresses the key once more winding II of relay Z3 and winding I of relay Y3 are short-circuited in the exchange VSt1 by contacts 105x3 and 134v5 which are arranged in series. Relay Z3 releases. At contact 122x3, relay V4 is switched on and energizes relay X4 over contact 124v4. This latter relay closes contact 125x4 thereby connecting the low resistance winding of relay V6 in parallel with winding II of relay Z4 and winding I of relay Y4. Relay Z4 releases. Relay V6 energizes and prevents the lamp UL4 50 55 60 being switched on at contact 128v6.

When the subscriber releases the key, contacts 105x3 and 122x3 open and relay Y3 falls back. In addition relay V4 de-energizes. Relay X4 falls back, contact 125x4 opens and relays Y4 65 and V6 release. The release of relay Y3 causes relay V5 in the exchange VSt1 to release upon the opening of contact 113y3. The connecting path reverts to the original condition obtained before the first inadvertent switching operation 70 on the part of the subscriber.

In the drawings it is shown that, when a connecting path is restored to its original condition after switching operations initiated by the operation of the key on the part of a subscriber 75

have become effective, all the control and switching over devices also revert to their original condition. This is, however, not always necessary. In the case of special forms of system or if special control devices, for example electro-magnetic switches, are used as controlling devices, the control and switching over devices can of course be brought to a condition other than that in which they were to be found before the subscriber initiated the switching operations. The only assumption made is that the connecting path as regards its operating condition always assumes the same condition, after all the switching operations have been effected by the subscriber, as that obtained before the switching operation took place.

What is claimed is:

1. In a telephone system, a switching device, a trunk line extending to a public exchange, a branch line associated with said switching device, means operative responsive to the seizure of said switching device by a calling subscriber for seizing said trunk line, means controlled by a manual operation a predetermined number of times by the calling subscriber for controlling said switching device to maintain said trunk line in its seized condition, for disconnecting said trunk line from said switching device, and for seizing said branch line to connect the calling subscriber thereto, and means for again connecting the calling subscriber to the seized trunk line responsive to the same manual operation by the calling subscriber a predetermined number of times prior to the completion of a connection over the seized branch line.
2. In a telephone system, a switching device, a trunk line extending to a main exchange associated with said device, a branch line over which inquiry calls are extended associated with said device, an incoming line over which a subscriber may seize said device, means in said switching device operative responsive to the seizure of said switching device by a calling subscriber for seizing said trunk line, means in said switching device controlled by a predetermined number of manual operations performed by the calling subscriber for maintaining said trunk line in a seized condition, for disconnecting said trunk line from said switching device, and for seizing said branch line and connecting the calling subscriber thereto, means in said switching device for repeating impulses transmitted by the calling subscriber over said branch line to complete a connection thereover, a timing device associated with said switching device, means for starting said timing device when said branch line is seized, means controlled by said timing device after a predetermined time interval has elapsed for disconnecting said branch line from said switching device and for again connecting the seized trunk line to said switching device and calling subscriber, and means in said switching device operated responsive to the transmission of the impulses for extending said connection over said branch line for preventing said timing device from performing said controlling operations.
3. In a telephone system, a switching device, a trunk line extending to a main exchange associated with said device, a branch line over which inquiry calls are extended associated with said device, an operator's line associated with said device and normally disconnected therefrom, an incoming line over which a calling subscriber controls said device, means in said device operative responsive to the seizure thereof by a calling subscriber for seizing said trunk line, means

in said device controlled by a predetermined number of manual operations by the calling subscriber for maintaining said trunk line in its seized condition, for disconnecting said trunk line from said device, and for seizing said branch line and connecting the incoming line thereto, a signal for the operator associated with said operator's line, means in said device controlled by said predetermined number of manual operations plus one additional manual operation by the calling subscriber for operating said signal, means controlled by the operator for maintaining said trunk line in its seized condition, for disconnecting said trunk line from said device, and for connecting said operator's line with said device and said incoming line, a timing device in said switching device, said timing device effective when impulses are not transmitted by the calling subscriber to control the extension of a connection via said enquiry line within a predetermined time interval for preventing any subsequent manual operation by the calling subscriber from controlling said operator's signal and for controlling said switching device to disconnect said branch line from said switching device and for reconnecting said trunk line to said switching device and incoming line.

4. In a telephone system, a switching device, a trunk line connected thereto, a first branch line, a second branch line, said branch lines associated with said device and normally disconnected therefrom, an incoming line over which a calling subscriber may seize and control said device, means in said device operative responsive to the seizure thereof by a calling subscriber for seizing said trunk line in order to complete a connection between the incoming line and the trunk line, switching means in said device controllable over said incoming line for disconnecting said incoming line from said trunk line, for seizing the first of said branch lines and connecting the incoming line thereto responsive to a predetermined number of manual operations by the calling subscriber, said switching means also controllable responsive to a predetermined different number of manual operations by the calling subscriber to disconnect said incoming line from said trunk line, to seize the second of said branch lines and to connect the incoming line thereto, means controlled by said switching means for holding said trunk line in its seized condition when either one of said branch lines is seized, said switching means effective to restore the initial connection between the trunk line and the incoming line prior to the completion of a connection over either one of said branch lines responsive to the same number of manual operations by the calling subscriber required to initiate the seizure of the first of said branch lines.

5. In a telephone system, a switching device, a trunk line connected thereto, a first branch line, a second branch line, said branch lines associated with said device and normally disconnected therefrom, an incoming line over which a calling subscriber seizes and controls said device, means in said device operative responsive to the seizure thereof by a calling subscriber for seizing said trunk line in order to complete a connection between the incoming line and the branch line, switching means in said device controllable over said incoming line by a single manual operation by the calling subscriber for disconnecting said incoming line from said trunk line, for seizing the first of said branch lines and for connecting the incoming line thereto, said switching device

- also responsive to the same manual operations being performed twice for disconnecting said incoming line from said trunk line, for seizing the second of said branch lines and for connecting 5 the incoming line thereto, means controlled by said switching means for holding said trunk line in seized condition when either one of said branch lines is seized, said switching means also operable responsive to two further similar manual 10 operations in quick succession by the calling subscriber to restore the initial connection between the trunk line and the incoming line after an inadvertent single manual operation has initiated the seizure of the first of said branch lines.
- 15 6. In a telephone system as claimed in claim 2, in which the timing device is a thermal relay that energizes after a predetermined elapsed time interval only when impulses are not transmitted by a calling subscriber within that elapsed time intervals.
- 20 7. In a telephone system as claimed in claim 2, in which the means controlled by the timing device is a relay that energizes and thereby initiates the disconnecting of the branch line and the re- 25 connecting of the seized trunk line.
8. In a telephone system as claimed in claim 1, in which the means controlled by the manual operation is a relay group.
9. In a telephone system, a repeater, a trunk 30 line over which connections are extended to a main exchange associated with said repeater, an incoming line over which a calling subscriber seizes said repeater, means in said repeater operated responsive to the seizure thereof for seizing
- said trunk line, a branch line over which enquiry connections may be extended by the calling subscriber while he holds the seized trunk line, means in said repeater controlled over said incoming line responsive to a single operation of a key by the calling subscriber for connecting said incoming line to said branch line and disconnecting said trunk line therefrom and for holding said trunk line in a seized condition, while the subscriber extends a connection over said branch line, a 10 second branch line extending to an operator's position, a signal at said position, means in said repeater controlled over said incoming line responsive to two operations of a key by the calling subscriber for operating said signal, and 15 means in said repeater controlled by the operator at said position for connecting said incoming line to said second branch line and for disconnecting said trunk line therefrom and for holding said trunk line in a seized condition. 20
10. In a telephone system as claimed in claim 9, in which said repeater may be controlled while said incoming line is connected to the first of said branch lines to disconnect the incoming line from the first of said branch lines and to reconnect it 25 to the held trunk line responsive to a further operation of the key by the calling subscriber or may be controlled while said incoming line is connected to said second branch line to disconnect the incoming line from said second branch line 30 and to reconnect it to the held trunk line responsive to the operation of a key by the operator at said position.

WALTER PINELL.
